DUPLEX LOUD-SPEAKER

Joseph Brami, Baltimore, Md., assignor to Caesar David Zeitouni, Brooklyn, N. Y.

Application January 6, 1949, Serial No. 69,541

23 Claims. (Cl. 179—115.5)

1

The invention relates to loud-speakers and more particularly to sound-chamber loud-speakers equipped with sectional reflex horns.

Loud-speakers of that type are widely used because of their compactness and light weight.

Adequate for general applications, these loud-speakers are unfortunately inappropriate for high-fidelity music reproduction owing to their restricted sound frequency range which covers generally the high to medium portion.

That is why they are mostly associated with large-diaphragm direct radiator loud-speakers which are acknowledged as good reproducers for the low frequency portion.

Such a combination, however, is expensive and cumbersome since it requires the use of two separated loud-speaker units.

A first object of the invention is to convert sectional reflex horn loud-speakers into wide-range duplex loud-speakers by replacing one of the sections of their reflex horn (preferably the external mouth-section) by the large diaphragm of a direct radiator loud-speaker separately operated.

A second object of the invention is a specially-designed, wide-range duplex loud-speaker achieving the aforesaid object and comprising a number of particular arrangements and advantageous features.

The invention, which furthermore includes other improvements, is illustrated in cross-section in the accompanying drawing in which Figure 1 is the wide-range duplex loud-speaker of the present application; and Figure 2, a modified portion of the same loud-speaker.

As shown in Figure 1, the wide-range duplex loud-speaker of the invention is composed of four principal, easily-separable parts: a sound-chamber reproducer 1, a single-fold reflex horn 2, a large-diaphragm direct radiator loud-speaker 3 and a double air gap magnetic structure 4 which is common to the sound-chamber reproducer 1 and to the direct radiator loud-speaker 3.

The magnetic structure 4 consists of an annular magnet 5 clamped by bolts 6, 6 passing through its slots 7, 7, between a bottom of a case 8 and a ring 9 which forms an outer annular air gap 10 with an edge of the case 8 and an inner annular air gap 11 with a central core 12 tightly fitted to a hole of the bottom of this case 8.

The sound-chamber reproducer 1 comprises a small dome-shaped diaphragm 14 which, attached to a voice coil 15 located in the inner air gap 11, has its flexible edge 16 glued between two rings 17, 17 which, fitted into a recess 13 provided by a shoulder 18 projecting the ring 9, are tightened by an exponential throat-case 19 which, screwing

2

on a thread 20 of the shoulder 18, has a tapped duct 21 and makes by its inner side with the facing side of the diaphragm 14, an enclosed clearance space 22.

5 The single-fold reflex horn 2, composed of a section 23 and another 24 having an annular-concave deflecting bottom 25 and mounted over the section 23 by riveted or welded brackets 26, 26, is screwed by its threaded throat 27 on the tapped duct 21 in order to communicate with the clearance space 22 of the sound-chamber reproducer 1.

The large-diaphragm direct radiator loud-speaker 3 consists of a housing 28 which, welded to a rim 29 fitted and clamped by machine screws 30, 30 to the magnetic structure 4, has an edge 31 to which is glued together with a felt ring 32, a corrugated edge 33 of a large exponential bell-like diaphragm 34 having an opened concave bottom 35 which, continued without contact by the exponential throat-case 19 in order to constitute an annular-concave deflector 36, is attached to a voice coil 37 guided in the outer air gap 10 by a corrugated spider 38 glued to a bottom edge 39.

10 The whole assembly is previously centered in order to insure the automatic centering of the voice coil 37 of the large diaphragm 34 in the outer air gap 10, when the magnetic structure 4 fits to the rim 29.

Owing to the deflector 36, the large diaphragm 34 of the direct radiator loud-speaker 3 serves at 15 the same time as a continuation of the single-fold reflex horn 2 by constituting the external mouth-section of a two-fold, three-section reflex horn 23, 24, 34 for the sound-chamber reproducer 1. The reflexed air-column of this horn 23, 24, 34 (visualized by the successive arrows) follows 20 this path; the throat 27, the section 23, the deflecting bottom 25, the space between the two sections 23 and 24, the deflector 36 and the space 25 between the section 24 and the diaphragm 34.

20 In the modification of Figure 2 (where the same numbers designate the same parts as in Figure 1), the wide-range duplex loud-speaker of the invention has its sound-chamber reproducer 1 placed at the back of the magnetic structure 4.

25 For that purpose, the ring 9 is replaced by a round plate 41 holding a core 42 which, extended by a centrally-holed convex plug 43 and provided with a tapered duct 44 ended by a tapped hole 45, forms a rear annular air gap 46 with a bottom 30 opening of the case 8. To avoid useless magnetic losses, the plug 43 is made of insulating material, such as Bakelite, hard rubber, plastics and the like. A back extension of this case 8 furnishes a shoulder 47 with a thread 48 and a recess 49 35 into which fit the rings 17, 17 supporting the

flexible edge 16 of the diaphragm 14 and tightened by a protective screw-cap 58 screwing on the thread 48. An enclosed clearance space 51 is constituted between the convex plug 43 and the facing side of the diaphragm 14. Passing freely through a hole 52 of an annular-concave bottom 53 provided by the large diaphragm 34 and making entirely by itself the deflector 36, the threaded throat 21 of the reflex horn 2 is screwed on the tapped hole 45 of the core 42 in order to communicate with the clearance space 51 of the sound-chamber reproducer 1.

It is obvious that the wide-range duplex loud-speaker of the invention necessitates the use of an electrical frequency-dividing network which, by separating the sound-modulated currents into two parts, permits to allocate them respectively to the voice coil 15 of the sound-chamber reproducer 1 and to the voice coil 37 of the direct radiator loud-speaker 3.

According to the dimensions of the diaphragm 34 and the length of the reflex horn 2, the direct radiator loud-speaker 3 and the sound-chamber reproducer 1 may be assigned to the reproduction of the following portions of the sound frequency ranges: (a) the speaker 3 to the low to medium frequencies, while the reproducer 1 to the high frequencies; (b) the speaker 3 to the low frequencies, while the reproducer 1 to the high to medium frequencies.

Of course the loud-speaker of the invention is not limited to the indicated number of sections for the reflex horn.

I claim:

1. In combination, a bell-like diaphragm positioned to discharge sound vibrations forwardly from within the diaphragm; means for introducing high frequency air vibrations rearwardly into the inner part of the diaphragm; and means for imparting low frequency vibrations to the diaphragm.

2. In combination, a small sound chamber; a diaphragm across the chamber; means for imparting high frequency vibrations to the diaphragm; a long narrow horn communicating at its inner end with said chamber and having its intermediate part remote from said inner end and its larger end adjacent to the inner end; a large single fold exponential direct radiator bell-like vibratory diaphragm receiving said horn and having its inner end freely movably closely adjacent to the larger end of the horn and forming a continuation thereof; and means attached to said inner end of the bell-like diaphragm for imparting low frequency vibrations thereto.

3. In combination, a large single fold exponential direct radiator bell-like diaphragm mounted for free vibration; and having a small inner end; means attached to said inner end of the bell-like diaphragm for imparting low frequency vibrations thereto; a small high frequency sound chamber; a long narrow reflex exponential horn communicating at its smaller end with said chamber and having its larger end disposed entirely within said diaphragm and discharging toward the inner end of the diaphragm; said diaphragm having its inner end freely movably closely adjacent to the larger end of the horn and forming an exponential continuation of the horn; whereby said bell-like diaphragm serves the multiple function of a direct radiator loud-speaker; and serves as the external mouth section and an exponential continuation of said horn.

4. In combination, a large single fold exponential direct radiator bell-like diaphragm

mounted for free vibration, and having a small inner end; means attached to said diaphragm for imparting low frequency vibration thereto; a small sound chamber to the rear of said inner end; a diaphragm across the chamber; means for imparting high frequency vibrations to the diaphragm; a long narrow reflex exponential horn communicating at its inner end with said chamber and disposed entirely within said diaphragm and having its larger end discharging toward the inner end of the diaphragm; said diaphragm having its inner end freely movably closely adjacent to the larger end of the horn and forming an exponential continuation of the horn; whereby said bell-like diaphragm serves the multiple function of a direct radiator loud speaker, and serves as the external mouth section of an exponential continuation of said horn.

5. In combination, a magnet having outer and inner air gaps; a diaphragm flexibly marginally secured to said magnet; a high frequency voice coil in the inner gap and attached to the diaphragm; a throat case spaced over said diaphragm and having a duct therethrough; and an exponential face around the duct; a reflex horn comprising an inner section mounted in said duct, and an outer section closed at the outer end and spaced from the inner section; and said face; a large exponential direct radiator single fold bell-like diaphragm substantially coaxial with the horn and having a flexibly supported flaring outer edge and an inwardly curved bottom freely movably closely spaced around and forming a continuation of said face; and a low frequency coil in said outer air gap attached to the inner edge of the large diaphragm.

6. In combination, a magnetic case having a bottom and a large opening opposite the bottom; a core secured to said bottom; an annular magnet secured to said bottom around said core; a magnetic ring secured on said magnet and spaced from said core and the edge of the opening to form outer and inner air gaps; a diaphragm disposed over the free end of said core and flexibly secured to said ring; a high frequency voice coil in the inner gap and attached to the diaphragm; a throat case secured over said diaphragm to form therewith a sound chamber and having an axial duct and having an exponential face therearound; a bowl-like exponential diaphragm having an inner margin freely movable around said face and forming an exponential continuation of the face; means for imparting low frequency vibrations to said inner margin of the diaphragm; an exponential reflex horn having its small end in said duct and its large end directed toward said face.

7. In combination, a member having a duct therethrough; and an exponential face around the duct; a reflex horn comprising an inner section secured at its inner end in said duct, and an outer section spaced around the inner section and extending to near said face and having at the outer end an end cap spaced from the inner section; a large exponential direct radiator single fold bell-like diaphragm substantially coaxial with the horn having an outwardly flaring free edge and an inwardly curved bottom freely movably closely spaced around the edge of and forming a continuation of said face of the member; and means flexibly supporting said free edge; means for imparting low frequency vibrations to the inner edge of the large diaphragm; and means for supplying high frequency vibrations in said duct.

8. In combination, a magnetic case having a bottom and a large opening in the top; a core

secured to said bottom and terminating substantially centrally of said opening in the plane of the opening; an annular magnet secured to said bottom around and spaced from the core and terminating near said plane; a magnetic ring secured on said magnet and spaced from said core and the edge of the opening to form outer and inner air gaps; a dome-shaped diaphragm disposed over the free end of said core and having a flexible marginal extension secured to said ring; a high frequency voice coil attached to the edge of the diaphragm and disposed in the inner air gap; an exponential throat case marginally secured to said ring over and conformably spaced from said diaphragm to form therewith a sound chamber and provided with an axial duct communicating with the sound chamber, and an exponential face around the duct; a bowl-like diaphragm having a freely movable inner margin forming a continuation of said face; a horn having its small end in said duct and its large end directed toward said face; and a low frequency voice coil attached to the inner edge of the large diaphragm and disposed in said outer air gap.

9. In combination, a member having a duct and an exponential face around the duct; a single fold reflex horn comprising an inner section tapering toward and secured at its inner end in said duct, and an outer section spaced from and enclosing the inner section and flaring toward and extending to near said face of the member and having at the outer end an end cap having an inner concaved face facing and spaced from the inner section; a bell-shaped loud speaker housing substantially coaxial with the reflex horn and having an inner end secured fast on said member around said face and having at its free edge a belt ring disposed in a plane transverse to the axis of the horn slightly beyond the outer end of the horn; a large exponential direct radiator single fold bell-like diaphragm conformably spaced from the loud speaker housing and having a transversely outwardly disposed flexible edge secured to said belt ring and a downwardly inwardly curved inner margin freely movably closely spaced around the edge of and forming a continuation of said face of the throat case; means connected to said inner margin for imparting low frequency vibrations to the large diaphragm; and means for supplying high frequency vibrations in said duct.

10. In combination, a magnetic case having a bottom having a large central opening and a larger opening in the top; a core spaced in said large opening of said bottom to form an inner air gap and terminating substantially centrally of said larger opening in the plane of the larger opening, and having an axial duct therethrough; an annular magnet secured to said bottom around and spaced from the core and terminating near said plane; a magnetic ring secured on said magnet and around the upper end of said core and spaced from the edge of said large opening to form an outer air gap; a convexed plug mounted on the rear end of the core and having a duct aligned with the duct of the core; a dome-shaped diaphragm conformably disposed over the plug conformably spaced from said plug to form therewith a sound chamber and communicating with said ducts, a high frequency coil attached to the diaphragm and disposed in the inner air gap; a freely vibratory bell-shaped diaphragm having a low frequency coil secured to its inner end and disposed in said outer gap; and a horn having a

small end in said duct, and a large end in said diaphragm.

11. In combination, a small sound chamber; a diaphragm across the chamber; means for imparting high frequency vibrations to the diaphragm; a single fold horn comprising an inner horn section tapering toward and communicating with said chamber, and an outer horn section spaced from and enclosing the inner section and flaring toward and spaced from said inner end and having at the outer end an end cap having an inner concaved face facing and spaced from the inner section; a large exponential direct radiator single fold bell-like diaphragm having a downwardly inwardly upwardly curved bottom freely movably closely spaced around the inner end portion of said inner section and forming exponential continuation of the outer section; and means attached to the inner part of the large diaphragm for imparting low frequency vibrations thereto.

12. In combination, a large direct-radiator diaphragm mounted for free vibration, and having a large outer end and a small inner end; means for imparting low frequency vibration to said diaphragm; a high-frequency chamber; a narrow horn communicating at its smaller end with said chamber and having its larger end near and forward of and discharging inwardly toward and against the inner face of the inner end part of the diaphragm; said diaphragm forming a continuation of the horn and reflecting the sound waves received from the horn; whereby said bell-like diaphragm serves the multiple function of a reflector and as a reflex wall for the horn and as a direct radiator loud speaker, and serves as the external mouth section and continuation of said horn.

13. In combination, a large single fold exponential direct radiator bell-like diaphragm mounted for free vibration, and having a large outer end and a small inner end; means attached to said diaphragm for imparting low frequency vibration thereto; a small high frequency compression chamber; a long narrow exponential horn communicating at its smaller end with said chamber and disposed within said diaphragm and having its larger end near and forward of and discharging toward the inner end of the diaphragm; said diaphragm having its inner end freely movably closely adjacent to the larger end of the horn and forming an exponential continuation of the horn and reflecting the sound waves received from the horn; whereby said bell-like diaphragm serves the multiple function of a reflector and as an outer reflex wall for the horn and as a direct radiator loud speaker, and serves as the external mouth section and as an exponential continuation of said horn.

14. In combination, a horn; means for introducing air vibrations into the horn; a hollow diaphragm mounted for free vibrations independently of the horn and positioned with its inner side facing the mouth of the said horn to form a reflex continuation of and an external mouth section for the horn; and means for imparting vibrations to the diaphragm.

15. In combination, a horn; means for introducing high frequency air vibrations into the horn; a hollow direct radiator diaphragm mounted for free vibrations independently of the horn and positioned with its inner side facing the mouth of the said horn to form a reflex continuation of and an external mouth section of the horn; and additional means for impart-

ing low frequency vibrations to the diaphragm.

16. In combination, a vibratory diaphragm positioned to direct sound vibrations forwardly from the front face thereof; means for imparting sound vibrations to the diaphragm for projecting the vibrations forwardly; an additional source of sound vibrations; a horn communicating at its smaller end with said source and having its larger end near and directed rearwardly toward the intramarginal part of the forward face of the diaphragm, to project the vibrations from the horn rearwardly from said larger end against the diaphragm to be combined with the vibrations thereof, to be reflected by the diaphragm, and projected with them forwardly from the face of the diaphragm.

17. In combination, a concaved vibratory diaphragm positioned to direct sound vibrations forwardly from the concaved face thereof; means for imparting low frequency sound vibrations to the diaphragm for projecting the low frequency vibrations forwardly from said concaved face; a source of high frequency sound vibrations; a horn communicating at its smaller end with said source and having its larger end near and directed rearwardly toward the mid-part of the forward concaved face of the diaphragm, to project the high frequency vibrations rearwardly from said larger end against the diaphragm to be reflected by the diaphragm, added to the low frequency vibrations and projected with them together forwardly from the forward face of the diaphragm.

18. In combination, a bell-like vibratory diaphragm positioned to direct sound vibrations forwardly from the concaved face thereof; means for imparting low frequency sound vibrations to the inner part of the diaphragm for projecting the low frequency vibrations forwardly; a source of high frequency sound vibrations; a horn communicating at its smaller end with said source and having its larger end near and directed rearwardly toward the mid-part of the forward face of the bell-like diaphragm, to project the high frequency vibrations rearwardly from said larger end against the diaphragm.

19. In combination, a vibratory diaphragm positioned to direct sound vibrations forwardly from its forward face thereof; means for imparting low frequency sound vibrations to the diaphragm for projecting the low frequency vibrations forwardly; a source of high frequency sound vibrations; a long narrow horn communicating at its inner end with said source and having its intermediate part remote from said inner end and its larger end adjacent to its inner end and directed rearwardly toward the mid-part of the forward face of the diaphragm, to project the high frequency vibrations rearwardly from said larger end against the diaphragm to be reflected by the diaphragm, combined with the low frequency vibrations and projected with them forwardly.

20. In combination, a high frequency sound chamber; a long narrow horn communicating at its smaller end with said chamber; a large direct radiator concaved vibratory diaphragm receiving the larger end and intermediate part of said horn and having its inner part freely movably closely adjacent to the larger end of the

horn; and means attached to said inner end of the diaphragm for imparting low frequency vibrations thereto.

21. In combination, a sound chamber; a long narrow horn communicating at its smaller end with said chamber and having its larger end adjacent to the inner end; a large concaved direct radiator vibratory diaphragm receiving said ends in its concavity and having inner part movably closely adjacent to the larger end of the horn and forming a continuation thereof; and means attached to the diaphragm for imparting vibrations thereto.

22. In combination, a high frequency sound chamber; a long narrow horn communicating at its inner end with said chamber and having its intermediate part remote from said inner end and its larger end adjacent to the inner end; a large direct radiator bell-like vibratory diaphragm receiving said horn in the space between the inner and outer ends of the diaphragm and having its inner end freely movably closely adjacent to the larger end of the horn and forming a continuation of, and external mouth for, the horn; and means attached to said inner end of the diaphragm for imparting low frequency vibrations thereto.

23. In combination, a concaved bell-like low frequency vibratory diaphragm positioned to direct sound vibrations forwardly from the concaved face thereof; low frequency means operatively connected to the mid-part of the diaphragm for imparting low frequency sound vibrations to the diaphragm for projecting the low frequency vibrations forwardly from said concaved face; a separate source of high frequency sound vibrations additional to said low frequency means; a horn communicating at its smaller end with said source and having its larger end near and directed rearwardly toward the mid-part of the forward concaved face of the diaphragm, to project the high frequency vibrations rearwardly from said larger end against the vibrating low frequency diaphragm to be reflected by the low frequency diaphragm, added to and combined with the low frequency vibrations and projected in combination with them forwardly from the forward face of the diaphragm, as an integral vibration, thus giving unified, firm, musical tone pattern.

JOSEPH BRAMI.
